ELECTRIC SWITCH

Filed Oct. 10, 1927

INVENTOR

George Henry Elwell

UNITED STATES PATENT OFFICE

GEORGE HENRY ELWELL, OF NEW HAVEN, CONNECTICUT, ASSIGNOR TO THE GREIST MANUFACTURING COMPANY, OF NEW HAVEN, CONNECTICUT, A CORPORATION OF CONNECTICUT

ELECTRIC SWITCH

Application filed October 10, 1927. Serial No. 225,195.

The invention relates to improvements in electric switches and more particularly to that type of an electric switch having an oscillating operating means. The applicant is aware that the development of the previous art discloses a swinging or oscillating contact making element having a sliding pivotal mounting upon one end and having a bearing at its opposite end adapted to ride upon the peaked cam of a reciprocating operating member, the swinging element being held engaged with the peaked cam by spring means supplying sufficient tension to cause the swinging element to snap over the peak of the cam as the reciprocating member is operated in opposite directions. In an application of even date herewith and filed October 10, 1927, Serial Number 225,194, the applicant discloses an electric switch element of that type with the swinging contact making element likewise associated with the peaked cam of the reciprocating member, but unlike the previous art the swing contact making element is pivotally mounted upon and carried by the reciprocating operating means. The present invention, while still associating the swinging contact making element with a peaked cam and pivotally mounting that element upon the member providing the peaked cam, provides an oscillating operating member to carry the swinging contact element and therefore the objects of this invention are to provide an electric switch of simple and economical construction; to provide an electric oscillating switch of that character capable of easy assembly within an electric lamp socket; to provide an electric oscillating switch contact carried by an oscillating operating member; and to provide an electric switch involving such other features of the invention as may herein appear.

The following is the description of an embodiment of the invention, the construction of which within the scope of what hereinafter is claimed may be varied without departing from the spirit or modifying any of the advantages of the invention. Reference being had to the drawing (one sheet) the Figure 1 is an upright elevation of an electric lamp socket without a casing but being provided

with an improved electric switch; Figure 2 is an elevation of the same socket illustrating an interior and the improved switch in open circuit position; Figure 3 is a cross-section view of the same socket at the line "A—A" of Figure 2; and Figure 4 is a perspective view of detail.

Referring more particularly to the drawing, in which similar parts are similarly numbered, the electric switch while adapted for association with any electrical device with which a switch may be desired is illustrated in the drawing in connection with an electrical lamp socket in which the supporting base, comprising the body of insulation 1, is provided with a center cavity 2, as best illustrated by Figure 3, communicating with a narrower but deeper cavity 3 extending therefrom radially to, and opening up, the cylindrical periphery of the body 1 and into the inclined portion 4 of the floor of the center cavity 2. Fixedly provided within the center cavity 2 are the center lamp and shell contacts 5 and 6, respectively, preferably mounted in spaced relation in a plane convergent with that in which the inclined portion 4 of the floor of the center cavity lies, as best illustrated by Figure 2. The oscillating switch 7 is provided at one end with a peaked cam 8 and at its opposite end with an operating handle 9. Located intermediate the cam 8 and the handle 9 are lateral projections 10, each adapted to become lodged within notches 11 located upon both sides of the opening in the periphery of the body 1 so that when the insulation lining (not illustrated) is placed over the notches 11 the lateral projections 10 will be locked thereby against dislodgment to serve as the pivot upon which the switch 7 oscillates, as best illustrated by Figure 2. Mounted upon and carried by the peaked portion 8 is the swinging expansible-against-tension spring device 12 adapted for a forced ascension under increasing tension up either incline of the peaked cam 8 and for an automatic instantaneous descent down the opposite incline upon the passing of the peak and release of the spring tension, as best illustrated by Figure 2. The spring device

12 is preferably made from a single piece of spring wire shaped to be pivotally mounted upon the oscillating switch member 7 at a particular point or within an elongated bearing 5 to provide a laterally shifting pivotal movement thereof if desired, the wire ends being inserted into the bearing and bent to secure the same therein and to extend therefrom as arms along both side surfaces 10 of the metal of the peaked portion 8 to the nearest part of the cam surface of the peaked cam 8 where each is made to assume the form of coils 13, the convolutions of which extend laterally in opposite directions, the 15 portion 14 of the wire connecting the coils lying across the cam surface of the cam 8. If, in the making of the spring device it is deemed expedient to employ such a light weight of wire that the portion 14 is likely to bendingly yield at the place of crossing instead of tensioning the coils, a tubular metal covering may be used to reinforce the wire at this place and also to serve as a roller bearing (not illustrated) of the spring device when riding on the peaked cam 8. From the foregoing it will be obvious that upon the oscillating movement of the switch element 7 the spring device 12, lying upon a low portion of one of the inclined surfaces 20 of the peaked cam 8 and against one of the convergent abutments, presented by the spaced abutments of the floor portion 4 as illustrated by the Figure 2 or the spaced contacts 5 and 6, one of which contacts is 25 illustrated by the Figure 2, the contact 6 being concealed by the contact 5, will continue to be arrested by such abutments as the oscillating switch element 7 is moved upon its pivot 10 and within the narrow cavity 3 and 30 forces one of its inclined surfaces of the cam 8 around and under the bearing 14 with the result that the bearing 14 is thereby lifted against the windingly increasing tension of the coils 13 until the peak of the cam is forced past the bearing 14 when, under the sudden unwinding release of the spring tension of the coils 13, the spring device 12 is swingingly precipitated down the other incline of the peaked cam 8 to and against the other 35 convergent abutments, as at 5 and 6 one of which is concealed by the other as illustrated by Figure 2, the contacts being thereby bridged, the spring switch 12 closes the electrical circuit of the electric lamp socket. 40

55 The screw-shell 18 is of the type disclosed in the Patent Number 1,762,512 granted to the applicant June 10, 1930, the screw-shell 18 having integral arms 19 and 20, best illustrated by the Figure 1, the arms 19 and 20 being secured to the insulation body 1 by the set-screws 21 and 22, respectively, of which either set-screw, as for instance the set-screw 21, may be used for a line contact from which the electrical circuit may be traced through 45 the arm 21, the screw-shell 18, a lamp screw-base (not illustrated), a lamp center contact (not illustrated), a socket center contact 23, the fixed contacts 5 and 6 bridged by the spring switch 12, and an arm 24 integral with the contact 6 and leading to the set-screw 25 providing the other line contact illustrated by the Figure 2. While the electric switch is illustrated in the drawing as having an oscillating movement within the lamp socket in a longitudinal direction the switch is as well adapted for such a movement in any predetermined direction so long as the associated construction of parts is in a relative way substantially similar as that herein described. When it is desired that this improved electric switch be used in connection with an electric lamp socket assembled within a unitary casing the handle 9 being made of insulation material may be provided with an attaching means adapted to be connected with the switch element by inserting the handle radially through a proper opening provided by both the casing and the lining (not illustrated) therefor. For this purpose the handle 9 may be provided with a bifurcated spring clip 15 at its inner end and adapted to be sprung into the grooves 16 with which the extremity of the member 7 is provided upon either side thereof, each section of the clip 15 having at its extremity a slightly off-set portion 17 adapted to form a shoulder for engagement under a shouldered end of its groove 16.

What I claim is:

1. An electric switch comprising a supporting base having a center cavity providing an oblique abutment, fixed contacts mounted within the cavity opposite the abutment and positioned relatively convergent thereto, a passage with which the base is provided communicating with the center cavity and extending through the abutment and between the contacts, an oscillating operating member mounted within the passage and being provided with a peaked switch-throwing cam; and a swinging spring switch member carried by the operating member and having a part adapted to ride upon the peaked cam within the cavity upon the movement of the operating member in either direction and alternate arresting engagement of the switch member with the abutment and the contacts to tension the switch member for a throwing movement upon passing the peak.
2. An electric switch comprising a supporting base of insulation having a cavity; fixed spaced contacts within the cavity; an oscillatory operating member having a peaked cam operable within the cavity, the operating member being mounted upon the supporting base; converging abutments provided by the base and by the spaced contacts; and an oscillatory spring switch carried by the operating member and having a part adapted to ride upon the peaked cam upon the

movement of the operating member in either direction and being alternately arrested by either of the abutments to tension the spring for a throwing movement to the other abutment upon passing the peak.

3. An electric switch comprising a supporting base of insulation having a cavity; fixed spaced contacts within the cavity; an oscillatory operating element having a peaked cam operable within the cavity, the operating element being mounted upon the supporting base; converging abutments provided by the base and by the spaced contacts; and an oscillatory spring switch mounted between the abutments and having a part adapted to ride upon the peaked cam upon the movement of the operating element in either direction and being alternately arrested by either of the abutments to tension the spring switch for a throwing movement to the other abutment upon passing the peak.

4. An electric switch comprising a supporting base of insulation having a cavity providing a pair of spaced abutments; fixed spaced contacts within the cavity and providing a pair of abutments relatively convergent to the insulation base abutments; an oscillatory operating switch element mounted upon the supporting base and having a peaked switch-throwing cam movable within the cavity and between both pairs of abutments; and a spring switch carried by the operating switch element, the spring switch having a part adapted to ride upon the peaked cam upon the movement of the operating switch element in either direction and the alternate arresting engagement of the spring switch part with a pair of abutments to tension the spring switch for a throwing movement against the other pair of abutments upon the passing of the peak by the spring switch part to alternately bridge the contacts to close the circuit.

GEORGE HENRY ELWELL.
